[57] CLAIM

The ornamental design for a sewing machine, as shown
and described.

DESCRIPTION

FIG. 1 is a top plan view of a sewing machine, showing
my new design;

FIG. 2 is a front elevational view thereof;

FIG. 3 is a bottom plan view thereof;

FIG. 4 is a rear elevational view thereof;

FIG. 5 is a left side elevational view thereof;

FIG. 6 is a right side elevational view thereof;

FIG. 7 is a front perspective view thereof; and

FIG. 8 is a rear perspective view thereof, with the han-
dle member in an upright position and with the spool
holder member in a retracted position.

FIG. 1

FIG. 2

FIG. 3

FIG. 4

FIG. 5

FIG. 6

FIG. 7

FIG. 8
